(57) **CLAIM**

The ornamental design for a sofa with foldable side table, as shown and described.

DESCRIPTION

FIG. 1 is a front, right, and top perspective view of a sofa with foldable side table showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view of the sofa with foldable side table of FIG. 1, shown in an alternate configuration of use; and,

FIG. 10 is another perspective view of the sofa with foldable side table of FIG. 1, shown in an alternate configuration of use.

The dash-dash broken lines in the drawings depict portions of the sofa with foldable side table that form no part of the claimed design.
